LACROSSE STICK

Elbert R. Nuttle, Jr., 308 Stanmore Road,
Baltimore, Md. 21212

Filed Mar. 18, 1966, Ser. No. 1,537

Term of patent 14 years

(Cl. D34—5)

The net has been omitted for convenience of illustration.

I claim:

The ornamental design for a lacrosse stick, as shown and described.
